UNITED STATES PATENT OFFICE.

WILLIAM LINDSAY, OF CHICAGO, ILLINOIS, ASSIGNOR TO STANDARD SANITARY MANUFACTURING COMPANY, A CORPORATION OF NEW JERSEY.

SIFTING APPARATUS.

1,120,950.

Specification of Letters Patent. Patented Dec. 15, 1914.

Application filed April 9, 1914. Serial No. 830,703.

To all whom it may concern:

Be it known that I, William Lindsay, a citizen of the United States, residing at Chicago, in the county of Cook and State of Illinois, have invented certain new and useful Improvements in Sifting Apparatus, of which the following is a description, reference being had to the accompanying drawings, forming a part of this specification, in which corresponding letters of reference in the different figures indicate like parts.

My invention relates to sifting apparatus for sifting fine powder such, for example, as Portland cement, enamel powder or analogous material; and my object is to so construct such a device as to enable the material to be sifted in a simple and economical way and that with the utmost certainty and uniformity by providing simple and efficient means to act upon the screen itself so as to rapidly distort the shape or contour of the meshes thereof in the plane of the screen and allow them to be restored to normal form—all of which is hereinafter more particularly described and definitely pointed out in the claims.

In the drawings—Figure 1 is a central vertical sectional view of a sifter embodying the features of my invention, a portion of the handle being broken, and parts of the electrical connections shown diagrammatically. Fig. 2 is a plan view thereof. Fig. 3 is an exterior view in elevation of the complete device. Figs. 4 and 5 are diagrams illustrating the manner in which the reticulated screen is distorted in action, and Fig. 6 is a central vertical section of a modified construction.

In reference to the drawings, 1 indicates the paper, by a flexible preferably cylindrical form, 2, of a projection toward the top sheet metal rounded or beaded at the top as shown in 3, and provided with an internal annular flange 3, at the bottom. A reticulated or net-like screen or sieve 4, preferably formed from fine woven wire, is stretched beneath the open bottom of the receptacle 1, so as to be under substantially uniform tension, and extended upwardly around the periphery thereof as shown at 5, Fig. 4, and rigidly secured in place by means of an inclosing band 6, having an inwardly turned bend 7 at the bottom upon which the receptacle is adapted to rest. Said band is

detachably secured in place by means of 55 bolts 8, to enable the screen to be replaced.

Secured to the receptacle by means of a bracket 9, or in any well known way, is a handle 10, preferably hollow, for the purpose hereinafter stated. Rigidly attached 60 to the inner walls of said receptacle by means of bolts 11, Fig. 1, and extending across the same, preferably diametrically, is a vibratory member generally designated by 12 which is formed from spring metal, preferably tempered steel. In the example illustrated in Fig. 1, which indicates what I regard as the preferred form, the several parts are integral, that is to say the vertical parts 13, 13, serve as means for securing the vibrator to the walls of the receptacle and also as supports for the horizontal parts or bars 14, 14, which are arranged parallel to each other and form in effect transverse tie rods between the walls of the receptacle. An 70 electro-magnet 15 has its core rigidly attached by means of screws 16, to the upper bar 14, with the poles of said magnet extending downwardly, while a like magnet 17, having its poles 75 extending outwardly 80 into operative proximity to those of its counterpart, is attached at 18, to the lower bar. The coils of said magnet are provided with leads 19, 20, which are extended through the bore in the handle 10, and connected in the 85 usual way with an alternating or intermittent current generator 21, Fig. 1. A normally open switch 22, Figs. 1 and 3, is preferably located in the handle 10, so that it may at all times be under the control of the 90 operator.

When the electric circuit is closed the magnets are alternately attracted and repelled, thereby causing a continuous vibration. When drawn together, the resilient 95 members or bars 14, are slightly bent, thereby shortening the distance between the parts 13, 13, and to that extent drawing the walls of the receptacle together, and distorting the body thereof from a circle to an ellipse.

The reticulated or net-like screen 4, is so placed with reference to the vertical plane in which the vibrator is located, that the latter will be oblique to the relative planes of the crossed or interwoven wires forming 100 the meshes; or in other words, said plane will extend diagonally across the row of substantially rectangular meshes beneath

the vibrator, so as to coincide with the two opposite corners thereof, if said wires are so placed as to lie in planes at angles of substantially forty five degrees from that 5 of said vibrator, as I prefer to have them placed.

In Figs. 2 and 4, I have shown the normal relation of the wires forming the screen. In Fig. 4 the circle represents diagrammatically the walls of the receptacle when in its normal state, while Fig. 5, shows it distorted, or in the form of an ellipse with a corresponding distortion, necessarily greatly exaggerated in degree, of the contour or 10 shape of the meshes of the screen, which distortion occurs with each attraction of the magnets, and the corresponding bending of the resilient members 14 of the vibrator, the distorting movement being horizontal, 15 or wholly in the plane of the screen instead of vertical. In practice I prefer to employ for very fine material a screen having about two hundred meshes to the inch. It follows therefore that the distortion in such a structure would not be perceptible to the eye. Nevertheless, I have found it to be thoroughly effective in practice.

In Fig. 6 I have shown a modified construction, in which all the parts are the 20 same except those substituted for the parts 14, and hence the reference numerals are retained as to all unchanged parts.

Extending across the receptacle, preferably in the plane of its diameter, is a bar 23, of spring metal, the ends of which are bent at right angles to the body and bolted to the walls of the receptacle by means of bolts 24. A magnet 17, having its poles pointing upwardly is rigidly attached to 25 the middle of said bar. A supporting arm 25, has one end jointedly connected at 26, to an adjusting bolt 27, which is passed through a bore in a lug 28, formed upon the bracket 9. An adjusting nut 29, adapted to be locked by a set screw 30, enables 30 said arm to be adjusted for the purpose hereinafter stated. The arm 25 is bent downwardly as shown and its lower end arranged to rest loosely upon the bar 23 at 35 any arbitrary point between the middle and end of the bar. Said arm is notched at its lower end so as to straddle the bar 23 and prevent lateral displacement. The magnet 15, is suspended beneath the arm 25, with 40 its depending poles in operative proximity to those of the magnet 17. The distance between the poles of the two magnets may be 45 adjusted by means of the set screws 29. When the magnets are excited the spring 50 bar 23 is caused to bend and draw the walls of the receptacle toward each other to a 55 proportionate degree, the action being the same in this respect as that of the preferred construction. In practice the distance be- 60 tween the opposing magnet poles should be

such as to prevent them from touching when excited. Such an adjustment enables the best results to be accomplished for sifting purposes while eliminating wear and preventing an unpleasant and injurious vibration of the handle.

The current frequency may be considerably varied in order to conform to the character of the material treated as well as the relative coarseness or fineness of the sieve. 70 For a comparatively coarse sieve the cycles may run as low as twenty five per second, while with one of extreme fineness they may exceed one hundred. It should be understood that the extent of distortion of the 75 sieve meshes would vary in proportion to the frequency of the electric vibrations; a low frequency giving a greater, and a high frequency a lesser degree of distortion. This feature should be taken into account in 80 connection with the relative fineness of the material to be treated.

I do not wish to be limited to any particular manner of adjusting the magnets with reference to a vibrator, nor do I wish 90 to be confined to electrical or magnetic means for accomplishing this purpose inasmuch as any automatic means for rapidly bending the bar or bars to distort the meshes of the screen may be employed.

The walls of the receptacle may be made more or less elastic and hence it follows that the connecting members between them may be mere light bands, wires or tie rods, the bending of which may serve to distort the walls as described. Nor is it essential that 100 these members should be placed diametrically so long as they are transverse to the body of the receptacle and arranged to cause a lateral distortion of the screen.

A peculiarly distinguishing feature of my device is that the sifting action is caused by a lateral distortion of the meshes in the plane of the screen instead of a substantially vertical vibration of the latter. The objection to vertical vibration is that there would be a maximum movement at the center of the screen and none at the edges, thereby causing irregularity in sifting, whereas, with the lateral distortion of the 110 meshes the sifting is uniform throughout the entire surface, which is of the utmost importance for enameling purposes or for use in which uniformity is essential.

Having thus described my invention, I 120 claim:

1. A sifter having a reticulated screen, yielding means attached thereto for normally holding the mesh forming members thereof in predetermined angular relation 125 to each other and means for rapidly distorting said holding means to change the angular contour of the meshes.

2. A sifter having a reticulated screen, a supporting frame for normally holding the 130

- mesh forming members at predetermined angles with relation to each other and vibratory means for distorting said frame to vary the angular form of the meshes of said screen.
3. A sifter comprising a receptacle having a net like screen the periphery of which is secured to the walls of said receptacle and means for drawing together and releasing said walls in rapid succession in planes oblique to those of the interwoven mesh-forming members.
4. A sifter comprising a receptacle having a reticulated screen secured to its walls, a transverse connecting member rigidly attached to said walls in a plane oblique to the planes in which the screen forming strands are located and vibratory means for rapidly bending said connecting member to impart a vibratory movement to the walls of said receptacle and thereby distort the meshes of said screen.
5. A sifter comprising a receptacle having a net like screen, the periphery of which is attached to the walls of said receptacle, a connecting member interposed between opposite walls of said receptacle and means for bending and releasing said member in rapid succession to distort the walls of said receptacle and the meshes of said screen.
6. A sifter comprising a receptacle having a screen secured to the walls thereof, a connecting member interposed between the walls of said receptacle, a magnet in operative proximity to said connecting member and electrical means for intermittently exciting said magnet to vibrate said member.
7. A sifter comprising a receptacle having a screen held under tension by the walls thereof, parallel connecting members interposed between the walls of said receptacle, opposing magnets supported respectively by said connecting members and electrical means for intermittently exciting said magnets whereby said connecting members may be set in vibration.
8. A sifter having a reticulated screen, yielding means for normally holding the wires thereof in stretched relation to each other to normally maintain the meshes in a predetermined form, and means for simultaneously exerting opposing forces in opposite directions at substantially opposite points upon said holding means to alternately contract and release the same to change the contour of said meshes and cause them to be returned to normal form.
9. A sifter having a reticulated screen, yielding means attached thereto for normally holding the mesh forming members thereof in predetermined relation to each other and means for rapidly exerting opposing forces at different points upon said holding means to alternately change the contour of the meshes and restore them to normal form.
10. A sifter having a reticulated screen, a supporting frame for normally holding the mesh forming members at predetermined angles with relation to each other and means for exerting opposing forces at different points upon said frame to vary the angular form of the meshes of said screen and restore them to normal shape.

In testimony whereof, I have signed this specification in the presence of two subscribing witnesses, this 30th day of March, 1914.

WILLIAM LINDSAY.
